ICEBREAKING VESSEL

Peter M. Kimon, Cos Cob, Conn., and Charles Lincoln
Crane, Jr., Madison, N.J., assignors to Esso Research
and Engineering Company

Filed Feb. 9, 1970, Ser. No. 21,327

Term of patent 14 years

Int. Cl. D12—06

U.S. Cl. D71—1

FIG. 1 is a front perspective view of an icebreaking vessel embodying our new design;

FIG. 2 is a side elevational view as seen from the right in FIG. 1; the side elevational view as seen from the left is a mirror image thereof;

FIG. 3 is a top plan view thereof;

FIG. 4 is a front elevation view thereof; and

FIG. 5 is a cross-sectional view taken substantially along the line 5—5 in FIG. 3.

We claim:

The ornamental design for an icebreaking vessel, substantially as shown and described.
